UNITED STATES PATENT OFFICE.

HIRAM C. FLETCHER, OF EDEN, VERMONT.

IMPROVEMENT IN MACHINES FOR CUTTING ROOTS.

Specification forming part of Letters Patent No. 35,928, dated July 22, 1862.

To all whom it may concern:

Be it known that I, HIRAM C. FLETCHER, of Eden, in the county of Lamoille and State of Vermont, have invented a new and Improved Device for Cutting Roots; and I do hereby declare that the following is a full, clear, and exact description of the same, reference being had to the accompanying drawings, making a part of this specification, in which—

Figure 1 is a side sectional view of my invention, taken in the line xx , Fig. 2. Fig. 2 is a plan or top view of the same.

Similar letters of reference indicate corresponding parts in the several figures.

The object of this invention is to obtain a device for cutting roots for the feeding of stock and other purposes which will be exceedingly simple, capable of being manufactured at a reasonable cost, and operate with less friction, and consequently with a less expenditure of power, than those previously constructed.

To this end the invention consists in the employment or use of a hopper provided with inclined ends and parallel vertical sides, having their lower edges curved to form a portion of a circle, against which a box is fitted and works, said box having the cutters fitted in it, and being suspended from a rock-shaft, all arranged as hereinafter fully shown and described.

To enable those skilled in the art to fully understand and construct my invention, I will proceed to describe it.

A represents a hopper, which is supported at a suitable height by any proper framing, B. This hopper is provided with inclined end pieces, aa , and parallel vertical side pieces bb the lower edges of the latter being rounded to form a portion of a circle, as shown at c in Fig. 1. A space or opening, d , is allowed between the lower ends of the end pieces, aa , and in this space or opening a cross-bar, C, is placed centrally, having its ends secured in the side pieces bb . This cross-bar extends down some distance below the lower ends of the end pieces, aa , as shown in Fig. 1.

To each side piece b of the hopper there is attached an upright, e , through the upper ends of which a shaft, D, passes, and to each end of said shaft a pendant, E, is attached. These pendants extend down one at each side of the

hopper A, and are attached at their lower ends to a bar, F, to the upper surface of which there are secured two curved or segment side pieces ff the upper surfaces of which are in contact with the lower curved surfaces, c , of the side pieces bb of the hopper, the curvature of the side pieces ff corresponding to the curvatures cc of the side pieces, as shown clearly in Fig. 1.

To the upper surfaces of the side pieces ff of the bar F there are secured horizontally two knives or cutters, G G, one being at each side of the bar F and parallel with it, and to each side of the bar F there are secured a series of vertical knives or cutters, H, at equal distances apart. The upper edges of the knives or cutters H are in contact with the inner and cutting edges of the knives or cutters G, as shown in Fig. 1.

The upper surface of the bar F is made of concave form, having a curvature corresponding to that of the side pieces ff , and the cross-bar C in the space or opening d at the bottom of the hopper just clears the upper surface of F. To the bar F there is attached a rod, I, which is connected to a hand-lever, J, at one side of the framing B.

The operation is as follows: The roots to be cut are placed in the hopper A, and a reciprocating motion is given the bar F and cutters G H by operating the lever J. The roots pass down on the bar F at each side of the cross-bar C, and are cut horizontally by the cutters G and vertically by the cutters H, the bar C serving as a bearing to hold the roots while the cutters are acting upon them. The cut roots are discharged between the cutters H. By this arrangement the cutters are operated with but little friction, in consequence of the bar F being suspended from the shaft D. The reciprocating cutter-slides, working in a plane, as hitherto devised, cause a great deal of friction even when the parts are well made and properly adjusted together, for the resistance the roots make to the action of the cutters causes the slide to bear at one side or the other against its guides, a contingency which cannot occur in my invention.

The cutters H should be rounded at their back parts—that is to say, be of elliptical form in their horizontal section—in order to cut through the roots easily.

I do not claim, broadly, a reciprocating slide

provided with cutters for cutting roots, for they have been previously used for that purpose; but

I do claim as new and desire to secure by Letters Patent—

1. The cutters G H when connected to swinging pendants E, so arranged that the cutters will move in the arc of a circle, substantially as and for the purpose set forth.

2. The construction and arrangement of the

parts to which the cutters are directly attached—to wit, the curved side pieces, f f, and bar F—when said parts are arranged with the lower curved ends of the side pieces b b of the hopper, to operate as set forth.

HIRAM C. FLETCHER.
